(57) **CLAIM**

The ornamental design for the bait station, as shown and described.

DESCRIPTION

FIG. 1 is a perspective view of the bait station of this invention;

FIG. 2 is a front elevation thereof, the rear elevation being a mirror image thereof;

FIG. 3 is a side elevation, the opposite side elevation being a mirror image thereof;

FIG. 4 is a top plan view;

FIG. 5 is a bottom view thereof; and

FIG. 6 is a perspective view of the bait station with the top cover removed;

FIG. 7 is a front elevation of the bait station with the cover depressed during activation; and,

FIG. 8 is a top plan view with the bait holding cover removed.
